his attorney.

UNITED STATES PATENT OFFICE.

ARTHUR S. ISAACS, OF PITTSBURGH, PENNSYLVANIA.

SHADE PULL.

Application filed November 1, 1922. Serial No. 598,320.

To all whom it may concern:

Be it known that I, ARTHUR S. ISAACS, a citizen of the United States, and residing in the city of Pittsburgh, in the county of Allegheny and State of Pennsylvania, have invented or discovered the new, useful, and Improved Shade Pulls of which the following is a specification.

My invention consists in certain new and useful improvements in pulls for spring-roller window shades and the like.

The type of shade-pull now in general use consists of a ring or other tension device attached to the center of the bottom edge of the shade, and with the same it is difficult to keep the shade straight, as it tends, when unwound or partially unwound to hang crooked, and, when wound up, to form a crooked roll on the roller. This presents a bad appearance, and also results in the shade becoming wrinkled and broken, and also frayed and torn along the edges.

The object which I have in view is the provision of improved pull means which will insure the straight unwinding of the shade and also of the straight winding up of the same on the roller, so that the shade will not only hang true with vertical lateral edges, but will also be properly wound up on the roller in the form of a roll with even ends.

For the accomplishment of these purposes I provide a new and improved shade pull wherein the tension on the shade is not exerted at the center of the bottom edge of the shade, but at either side of said center, at two points sufficiently spaced from said center to prevent torque when the pull is used. Such points of attachment are preferably nearer the ends than the center, thereby keeping the vertical edges of the shade straight and true.

In my invention shown in the drawings, at these two points, on either side of the center of the shade, I attach the ends of a connecting member, which is preferably a flexible cord or wire, and to said connecting member I attach a depending tension member adapted to be grasped by the fingers for the purpose of exerting a pull or jerk to the shade.

I provide a slipping connection between the connecting member and the tension member, as for instance, a sliding ring or grooved pulley, to which the tension mem-

ber is attached, running on the connecting member, thus automatically adjusting the pull or jerk to the action of the roller.

In the accompanying drawings, Fig. 1 is an elevation showing my invention applied to a shade mounted on a window; Fig. 2 is an enlarged broken perspective of the shade.

The following is a detailed description of the drawings.

A represents the window frame to which is applied the shade B mounted on the usual spring roller C.

The bottom of the shade is shown provided with the usual hem 1 in which is slipped the wooden stick or other stiffener 2.

At either side of the center of the bottom edge of the shade, and preferably adjacent to the ends thereof, I apply the spring metal clasps 3 which encompass the lower portion 70 of the shade. 4 represents the connecting member stretched or extending, preferably tautly, between the clasps 3, and tied or otherwise firmly secured to the clasps.

5 represents the depending tension member, which may be a short cord with a ring 6 on its lower end.

I attach the tension member 5 to the connecting member 4 by means slideable on the connecting member. Thus, I have shown a metal ring 7 running on the connecting member 4 and to which the tension member 5 is attached.

It is quite evident that any pull or jerk exerted on the tension member will be transferred to the rigid, bottom edge of the shade in such a manner that the vertical edges of the shade will remain straight and true, and the shade will be wound evenly on the roller.

This is due to the fact that the point of pull is not fixed at the center of the shade, but accommodates itself to the direction of the application of the force, so that the pull is exerted in a direction normal to the roller, thus insuring uniform winding and unwinding.

What I desire to claim is:—

1. In a shade pull for use in connection with a spring-roller shade, the combination of a flexible cord attached at its ends to the edge of the shade at equal distances on either side of the center of the latter, and a pull cord having its end connected to said first named cord and freely slideable along 110

the latter whereby the application of the pull is maintained normal to the spring-roller.

2. For use in connection with a depending spring-roller shade, a shade-pull comprising a freely depending tension member and means connecting said tension member to the bottom edge of said shade at opposite

sides of the center of the shade, and means whereby the point of application of the pull automatically shifts so that the pull is always exerted in a direction normal to the roller. ¹⁰

Signed at Pittsburgh, Pa., this 27th day of Oct., 1922.

ARTHUR S. ISAACS.
